(57) **CLAIM**

The ornamental design for three gate container, as shown and described.

DESCRIPTION

FIG. 1 is a top perspective view of the three gate container according to the present invention;

FIG. 2 is a top perspective view of the lid for the container shown separately for clarity;

FIG. 3 is a left side view of the lid for the container shown separately for clarity;

FIG. 4 is a right side view of the lid for the container shown separately for clarity;

FIG. 5 is the front side view of the lid for the container shown separately for clarity;

FIG. 6 is the back side view of the lid for the container shown separately for clarity;

FIG. 7 is the plan top view of the lid for the container shown separately for clarity;

FIG. 8 is a bottom plan view of the lid for the container shown separately for clarity;

FIG. 9 is a top perspective view of the base for the container shown separately for clarity;

FIG. 10 is a left side view of the base for the container shown separately for clarity;

FIG. 11 is a right side view of the base for the container shown separately for clarity;

FIG. 12 is a front side view of the base for the container shown separately for clarity;

FIG. 13 is a back side view of the base for the container shown separately for clarity;

FIG. 14 is a top plan view of the base for the container shown separately for clarity; and,

FIG. 15 is a bottom plan view of the base for the container shown separately for clarity.
